UNITED STATES PATENT OFFICE.

REGINALD F. HALLIWELL, DECEASED, LATE OF LEAMINGTON SPA, ENGLAND, BY
SIGNE EMILIA HALLIWELL, EXECUTRIX, OF LEAMINGTON SPA, ENGLAND, AS-
SIGNOR TO GENERAL ELECTRIC COMPANY, A CORPORATION OF NEW YORK.

ELASTIC-FLUID TURBINE.

Application filed December 3, 1925, Serial No. 73,036, and in Great Britain December 11, 1924.

This invention relates to elastic fluid turbines of the type having both high and low pressure stages and has for its object to provide improved means for controlling the admission of elastic fluid to the low pressure stages.

According to the present invention, the supply of fluid to the low pressure stages is regulated by means of a sliding ring valve 10 which is movable in an axial direction relative to its seating under the control of suitable governing means. The governing means may be arranged to move the ring in a circular direction in response to a change in the operating conditions of the turbine, in which case the ring is so mounted that such circular movement effects a corresponding axial displacement of the ring, as, for example, by arranging diagonally disposed keys on the 20 ring support to engage in corresponding grooves in the internal face of the ring. The circular movement of the ring may be effected by a rack, or other suitable gear, operated by a servo-motor, the fluid supply to 25 the cylinder of which is controlled by suitable governing means such as a speed governor, a pressure responsive device, or a combination of the two.

For a consideration of what is believed to 30 be novel and the invention, attention is directed to the accompanying description and the claims appended thereto.

Referring to the drawing, Figs. 1, 2 and 3 are respectively a part sectional elevation, a 35 section on line A—A of Fig. 1, and a section on line B—B of Fig. 2 of a mixed pressure turbine, and Fig. 4 is a part sectional elevation of an extraction turbine.

Referring first to Figs. 1, 2 and 3, 1 represents the turbine shaft on which are 40 mounted a wheel 2 carrying rotor blades 3 at its periphery and forming a high pressure stage, and a wheel 4 carrying rotor blades 5 at its periphery and forming a low pressure 45 stage. The high pressure steam enters at 6 and passes through high pressure nozzles 7 and the blading 3, being discharged through a ring of nozzles 8 and the blading 5 of the low pressure stage. Low pressure steam enters 50 at the opening 9 and is arranged to pass by way of ports 10 to a ring of nozzles 11 and the blading 5.

The admission of low pressure steam to the ports 10 is controlled by means of a slid-

ing ring valve 12, which is arranged to be 55 partially rotated through a rack 13, or other suitable gearing, by means of a servo-motor 14, the fluid supply to the cylinder of which is controlled by a speed governor, a pressure responsive device, or a combination of the 60 two. The arrangement of the governing means in connection with the servo-motor is not illustrated, as such arrangements are well known. Any suitable means may be utilized. The ring valve 12 is provided with 65 diagonal grooves 15 on its internal face, as shown in Fig. 3. These grooves engage with keys 16 fixed on a diaphragm 17 on which the valve rotates. With this arrangement, when the valve 12 is moved in a circular direction by the governing means, it is caused to move axially, thus approaching or receding 70 from a seating 18.

In the extraction turbine shown in Fig. 4, 75 in which the various parts have been numbered to correspond to those in Figs. 1, 2 and 3, but with the exponent a added, part of the steam leaving the high pressure stages is led through the opening 9^a for heating or other industrial purposes. The steam which is required to pass through the low pressure stages to develop the necessary power is admitted through the ports 10^a to a ring of nozzles 11^a and then through the low pressure stages. The admission of steam to the 80 ports 10^a is regulated by the valve 12^a in a similar manner to that described with reference to Figs. 1, 2 and 3.

A ring valve structure embodying the invention has the advantage that it provides 90 for complete peripheral flow of elastic fluid past it so that it gives an even distribution of the elastic fluid to the nozzles. At the same time, it lends itself to being manufactured readily and is easily operated. Also, it possesses the advantage that it is well adapted for use in cases where the elastic fluid which it controls is of comparatively high pressure, since it may be constructed so that it is practically balanced.

In accordance with the provisions of the patent statutes, the principle of operation of the invention has been described, together with the apparatus which is now considered to represent the best embodiment thereof, but 105 it should be understood that the apparatus shown is only illustrative and that the invention may be carried out by other means.

What is claimed as new and desired to be secured by Letters Patent of the United States is:—

1. The combination with an axial flow elastic fluid turbine having a rotor, of an annular valve means controlling the flow of elastic fluid to the low pressure stages and surrounding the rotor, said valve means comprising an axially-extending annular wall past which the elastic fluid flows, an annular ring valve slidably mounted on said wall, diagonally-disposed keys between the ring and wall, and means for moving said ring circumferentially to effect axial movement of the ring. 45
2. In an axial flow elastic fluid turbine having a rotor, valve means controlling the flow of elastic fluid comprising a radially-extending annular wall forming a valve seat, an axially-extending annular wall adjacent thereto, said walls surrounding the rotor, a ring valve seated on said axially-extending wall, and means for moving it axially thereon into and out of engagement with the radially extending wall. 50
3. In an axial flow elastic fluid turbine having a rotor, valve means controlling the flow of elastic fluid comprising an interstage diaphragm having a radially-extending annular wall forming a valve seat, an axially-extending annular wall connecting said first-named wall with the diaphragm, said walls concentrically surrounding the rotor, a ring valve slidably mounted on said axially-extending wall, diagonally disposed keys connecting the ring valve and wall, means for turning the ring valve to effect axial movements of it on said keys into and out of engagement with the valve seat, and conduit means in said diaphragm controlled by said ring valve. 55
4. The combination with an axial flow elastic fluid turbine having a rotor, of an annular valve means for controlling the flow of elastic fluid therein, said means comprising an annular ring surrounding the rotor and forming a movable valve, an interstage diaphragm having an annular axially-extending wall on which the ring is slidably and rotatably mounted, means providing an annular radial seat for one end of the ring, a plurality of ports in said wall covered by said ring, means for moving said ring to uncover said ports, and means connecting said ring and wall for carrying the ring axially when the ring is rotated. 60
5. In an axial flow elastic fluid turbine, an annular interstage diaphragm having an axially extending annular wall and an adjoining radial wall providing a valve seat, an annular ring valve having diagonally extending grooves on its inner face slidably mounted on said axially extending wall to move into and out of engagement with said valve seat, diagonally disposed keys carried by the annular wall with which keys the diagonally extending grooves in the valve ring engage to guide the valve in its movement, means connected with the valve to move it on said keys into and out of engagement with the valve seat, a ring of nozzles carried by the diaphragm, and a plurality of ports in said diaphragm which communicate with the nozzles, said ports having inlet ends in said annular wall adjacent the valve seat whereby they are uncovered as the valve moves in a direction away from the seat. 65

In witness whereof I have hereunto set my hand this 11th day of November, 1925.

SIGNE EMILIA HALLIWELL,
*Executrix of the last will and testament of
Reginald F. Halliwell, deceased.*
